[57] CLAIM

The ornamental design for a paint tray, as shown and described.

DESCRIPTION

FIG. 1 is a perspective view of a paint tray showing my new design;

FIG. 2 is a side elevational view, the opposite being a mirror image thereof;

FIG. 3 is a front elevational view thereof;

FIG. 4 is a bottom plan view thereof; and

FIG. 5 is a modified form of the paint tray shown in FIG. 1 wherein the only difference resides in the two opposite walls which are each inclined and have similar supporting legs.

FIG.1.

FIG.2.

FIG.3.

FIG.4.

FIG. 5.
